(57) **CLAIM**

The ornamental design for a power outlet camera, as shown and described.

DESCRIPTION

FIG. 1 is a top, front and right side perspective view of a power outlet camera embodying the new design;

FIG. 2 is a top, rear and left side perspective view thereof;

FIG. 3 is a front elevation view thereof;

FIG. 4 is a rear elevation view thereof;

FIG. 5 is a left side elevation view thereof; the undisclosed right side elevation being a mirror image thereof;

FIG. 6 is a top plan view thereof;

FIG. 7 is a bottom plan view thereof; and,

FIG. 8 is a front elevation view thereof, depicting a power outlet in broken lines to illustrate environment and forms no part of the claimed design.
